PHASE MODULATING SYSTEM

Juichi Osawa, Mita, Shibaku, Tokyo, Japan, assignor to Western Electric Company, Incorporated, New York, N. Y., a corporation of New York

Application July 31, 1934, Serial No. 737,696
In Japan August 24, 1933

6 Claims. (Cl. 179—171)

This invention relates to modulating systems and particularly to those in which the phase of a carrier wave is varied in accordance with signals.

5 The general object of the invention is to translate a signal wave into a succession of phase variations in a carrier wave.

A specific object is to diminish amplitude variations of the carrier wave in the process of 10 phase modulation.

Existing systems of phase modulation which insure a close correspondence between phase variation and signal amplitude show very little amplitude variation provided the phase change 15 is relatively small. If this range be exceeded, the accompanying amplitude modulation may be great.

In accordance with the invention, a carrier wave of substantially fixed amplitude and variable phase is generated by means of a vacuum tube having a reactive feedback connection between its plate and grid circuits. The voltage fed back to the grid circuit is in fixed quadrature relation with the grid voltage. The resultant 20 vectorial value of the sum of the grid voltage and the feedback voltage is always substantially equal to the impressed carrier voltage, which latter may be supplied from a constant voltage source. The grid and feedback voltages may be varied 25 by means of a source of signal waves but the quadrature relation of the voltages will hold throughout the variation. Furthermore, the load impedance offered by the vacuum tube to the carrier source is not materially affected by the 30 introduction and operation of the signal source. The locus of the grid potential is given in the vector representation by a circular arc. The radius vector, which corresponds to the voltage between the grid and the midpoint of the carrier 35 source, has the properties here desired. Accordingly, the output wave is taken from across these points, thus insuring a phase modulated wave free from amplitude modulation.

The invention will be more fully understood 40 from the following detailed description in conjunction with the drawing, of which,

Fig. 1 shows a preferred embodiment of the invention; and

Fig. 2 is a vector diagram useful in explaining the operation of the system of Fig. 1.

In Fig. 1, a modulator tube 1 is shown connecting a carrier source 2 to an amplifier 3 and an antenna system 4. The carrier source is connected to the grid of tube 1 by means of a transformer 5 having a divided secondary winding

with sections 6 and 7 and midpoint 8. A feedback transformer 9 has one winding connected to the grid of tube 1 and the other connected between the plate and cathode of tube 1 through a series tuning condenser 10. A signal source 11 is connected to the grid of tube 1 by means of an input transformer 12. The grid circuit of amplifier 3 is connected between the grid of tube 1 and the transformer midpoint 8. The output circuit of amplifier 3 is coupled to the antenna 10 system 4 in an entirely conventional manner.

In the operation of the system of Fig. 1, the carrier generator 2 develops a carrier voltage across the secondary windings 6 and 7, the value of which voltage in each winding is denoted by $E/2$. In the absence of feedback, the entire voltage E is impressed between the grid and cathode of tube 1. With the feedback circuit connected, as shown, a carrier current, denoted by I_P , in the plate circuit develops a feedback voltage, denoted by E_M , across transformer 9. The carrier voltage between grid and cathode, designated E_G , is modified by the feedback, but is always determined by the equation.

$$E = E_G + E_M, \quad (1)$$

in which each voltage is required to be expressed as a vector quantity.

The plate circuit of tube 1 may be tuned to 30 the carrier frequency by means of the condenser 10. At resonance the only material impedance 35 of the plate circuit is the internal plate-to-cathode resistance which is herein designated R_0 and has a conductance value equal to the reciprocal of R_0 which will be called S . The carrier plate current I_P is then given by the equation

$$I_P = \frac{\mu E_G}{R_0} = \mu E_G S, \quad (2)$$

where μ is the amplification factor of the tube.

The voltage across either the transformer 9 or the condenser 10 is in quadrature with the plate current and proportional thereto. In the system 45 illustrated, the feedback voltage is taken from the transformer and is proportional to its mutual impedance. The feedback voltage is then determined by the equation

$$E_M = j\omega M I_P, \quad (3)$$

where j is the operator indicating quadrature, ω is 2π times the carrier frequency and M is the mutual inductance of the transformer 9.

Substantially Equation (2) in Equation (3) gives

$$E_M = j\omega M\mu E_G S, \quad (4)$$

which indicates that E_M and E_G are always in quadrature with each other although their relative values may vary. Since the vector sum of E_M and E_G is always equal to the impressed voltage E , it is evident that the locus of the grid potential must lie upon a circular arc in the vector field. This relation is shown in Fig. 2 wherein E_G and E_M are plotted at right angles and of such relative magnitudes as to sum up vectorially to the value E . The phase angle between E_G and E is denoted by $\frac{1}{2}\phi$. While this angle is variable by changing either E_G or E_M , the latter by varying S , the vector E_G always terminates upon the semi-circular arc having E as the diameter.

Inspection of Fig. 2 reveals that the radius vector lies between the midpoint of the diameter and the junction of E_G and E_M . This vector has a constant length $\frac{1}{2}E$ and a variable phase angle ϕ . The vector corresponds to the voltage generated in the system of Fig. 1 between point 8 and the grid of tube 1. The voltage between these points is denoted E_0 and is impressed between the grid and cathode of amplifier 3. In this way a voltage of constant amplitude and variable phase is impressed on the amplifier 3 and delivered in amplified form to the antenna system 4. The phase is varied by means of the signal source 11 shown connected to the grid circuit of tube 1 in a well known manner to vary the plate circuit conductance in accordance with a signal wave.

What is claimed is:

1. A phase modulating system comprising a vacuum tube with a cathode, an anode and a control grid, a divided carrier source with accessible midpoint, the outer terminals of said source being connected respectively to the grid and the cathode of the tube, means to feed back a carrier wave from the anode circuit to the grid circuit in quadrature with the instantaneous carrier voltage between the grid and the cathode, a load circuit bridged between the midpoint of the carrier source and the grid of the tube, and a signal source adapted to vary the anode current of the tube, whereby the phase of the carrier voltage across the load circuit is varied at a signal rate while the amplitude of said carrier voltage is rendered substantially independent of the signal.

2. A phase modulating system comprising a vacuum tube with a cathode, an anode and a control grid, a divided carrier source with accessible midpoint, the outer terminals of said source being connected respectively to the grid and the cathode of the tube, an anode circuit including a branch series resonant to the carrier frequency, means to transfer into the grid circuit a voltage developed across one element of said series resonant branch, a load circuit connected between the grid of the tube and the midpoint of the carrier source, and a signal source adapted to vary the anode current of the tube, whereby the phase of the carrier voltage across the load is varied while the amplitude of said carrier voltage remains unchanged.

3. A phase modulating system comprising a vacuum tube with a cathode, an anode and a control grid, a divided carrier source with an accessible midpoint, the outer terminals of said source being connected respectively to the grid and the cathode of the tube, an inductance and a capacitance connected in series between the anode and the cathode of the tube, said inductance and capacitance being resonant to the carrier frequency, inductive coupling means to couple said inductance with the grid of said tube, a signal source adapted to vary the anode current of the tube, and a load circuit connected between the grid of the tube and the midpoint of the carrier source, whereby phase modulation of the carrier source is effected substantially without amplitude modulation.

4. A phase modulating system comprising two vacuum tubes, each having a cathode, an anode and a control grid, a divided carrier source with an accessible midpoint, the outer terminals of said source being connected respectively to the grid and the cathode of the first tube, means to feed back a carrier wave from the anode of the first tube to its grid in quadrature with the instantaneous carrier voltage between said grid and cathode, a signal source adapted to vary the anode current of the first tube, said second tube having its grid and cathode terminals connected respectively to the grid of the first tube and the midpoint of the carrier source, whereby the anode current of the second tube is phase-modulated without material amplitude modulating effect.

5. A phase modulating system comprising a vacuum tube with a cathode, an anode and a control grid, a transformer with a divided secondary winding, a carrier source connected to the primary winding of the input transformer, the extremities of the secondary winding being connected respectively to the grid and the cathode of the tube, means to feed back a carrier wave from the anode to the grid in quadrature with the instantaneous carrier voltage between the grid and the cathode, a load circuit connected between the grid of the tube and the midpoint of the secondary winding of the transformer, and a signal source adapted to vary the anode current of the tube, whereby the phase of the carrier current in the load is varied at a signal rate while the amplitude of the carrier current is substantially constant.

6. A phase modulating system comprising a vacuum tube with a cathode, an anode and a control grid, a divided carrier source with an accessible midpoint, the outer terminals of said source being connected respectively to the grid and the cathode of the tube, means to feed back a carrier wave from the anode to the grid in quadrature with the carrier voltage existing between the grid and the cathode, a load circuit bridged between the midpoint of the carrier source and the grid of the tube, and a signal source adapted to change the internal anode-cathode resistance of the tube, whereby phase modulation free from objectionable amplitude modulation is effected.
